FILAMENT STRUCTURE

Howard D. Doolittle, Stamford, Conn., assignor to Machlett Laboratories, Incorporated, Springdale, Conn., a corporation of Connecticut

Application May 27, 1952, Serial No. 290,173

3 Claims. (Cl. 313—264)

This invention concerns a novel filament structure for use in high power electron tubes. More specifically, this invention concerns an elongated, multiple hairpin filament structure of great simplicity, which structure is unsupported by the electron tube envelope at one end.

Because the interelectrode spacing in power tubes is small relative to the length of their electrodes, the opportunity for the filament to short into the grid or the anode is great. Moreover, certain forces, such as electromagnetic and/or electrostatic forces, act upon the filament strands in such a manner that the strands tend to be driven apart and into the adjacent electrode. In order to provide a stable structure which will resist the effects of such forces, most kinds of prior art filament structures have been supported by the tube envelope at both ends. Support at one end has been furnished by support-conductors which are in turn supported by a stem press or other portion of the vacuum envelope. Support at the other end has frequently been furnished by a center mast which is supported by the stem press or otherwise. The center mast either provides means for keeping the filament tight through spring tensioning or else it provides guides or eyelets through which the filament strands pass, thereby permitting free expansion of the filament but only in a predetermined direction.

In addition to complicating the tube structure, a center mast is subject to failure due to sticking of the tensioning mechanism or adherence of the strands to the guides or eyelets. Furthermore, each of the relatively massive support members of the center mast is capable of cooling that portion of the filament which it contacts as well as adjacent filament portions. If the amount of this cooling were constant, the amount of reduced emission could be taken into consideration in designing a tube. However, the cooling, hence the emission, varies considerably due to expansion effects which, in some cases, cause the filament to be in various degrees of good and bad contact with the support at different times and entirely out of contact with the support at other times.

Attempts to eliminate the center mast have been successful in the so-called squirrel cage, free-hung filament, but elimination of the center mast in other types of filament structures has heretofore been considered impossible. For instance, elimination of the center mast in tubes employing high voltage, low current filaments has not been considered possible, despite the advantage to be had in this widely used type of filament.

My invention provides a filament structure, one end of which is unsupported by the vacuum envelope. The active portion of this filament structure may be described as of elongated, closely spaced saw-tooth or multiple hairpin shape. This active portion of the filament consists of refractory metal wire formed into a plurality of hairpin bights and arranged with all strand ends at that end of the filament which is supported by the vacuum envelope. In a preferred form of my filament structure, a single strand of refractory wire is formed into a plurality of reverse hairpin bights so that alternate bights

2

define opposite ends of the active filament structure. The filament strand ends are in every case affixed to support-conductors which are, in turn, ultimately supported by the vacuum envelope. By my invention bights at the unsupported end of this filament structure are joined together through a non-conductive connection which opposes the electromagnetic and electrostatic forces tending to drive the otherwise unsupported bights apart and into the grid or anode structure. Thus, it is unnecessary with a structure of my invention to supply a center mast or any other support structure attached to the vacuum envelope for the purpose of lending support to the otherwise unsupported end of the filament structure.

For a better understanding of my invention reference is made to the following drawings:

Fig. 1 illustrates in partial section an electron tube which employs a three bight filament structure of my invention.

Fig. 2 is an elevational view of the active portion of the filament structure shown in Fig. 1, but rotated 90° around the major tube axis.

Fig. 3 is an elevational view similar to that of Fig. 1 which shows an enlarged view of the filament in the same position seen in Fig. 1.

Fig. 4 shows in elevation a filament structure of my invention which employs more than three bights.

Fig. 5 shows the structure of Fig. 4 rotated 90° around the major tube axis.

Fig. 6 is a plan view from above the unsupported end of filament structure of Figs. 4 and 5 showing one type of bracing which may be employed.

Fig. 7 is a view similar to Fig. 6 showing another type of bracing which may be substituted for that of Fig. 6.

Referring to Fig. 1 a high power triode electron tube is illustrated. The vacuum envelope of the tube is composed of a cylindrical glass section 10 closed at one end by a reentrant glass portion 11 and closed at the other end by a deep cup of copper 12 which provides the anode for the tube. Copper cup 12 may have a feather edge 12a at its lip in order to facilitate making the glass-to-metal seal joining the two envelope portions 10 and 12. Anode heat dissipation may be easily accomplished in this tube by water-cooling or by air-cooling the outside surface of anode 12. Water cooling is facilitated by support of the tube in a water jacket at collar 12b.

A tubular glass extension 14 of the reentrant portion 11 of the vacuum envelope which extends inwardly into the vacuum envelope has sealed to its end a metallic grid support member 15 of generally conical shape. The grid support is joined to a ring 16 which in turn supports a plurality of posts 17 which parallel the tube axis. The active grid 18 consists of a helical winding of refractory metal wire around and affixed to these support posts 17. The grid terminal 19 may be a small metallic cup

whose lip is sealed vacuum tight to a portion of the vacuum envelope. Conductive connection member 20 will provide an electrical connection between support cone 15 and terminal member 19.

The active filament which is shown in elevation in Figs. 1, 2 and 3, is supported on a pair of rod-like support-conductor members 22 and 23. These members may be sealed through the vacuum envelope by using a conventional stem press if desired. However, as shown, support-conductor 23 is sealed vacuum tight through metallic cup member 24 which in turn is sealed vacuum tight to the envelope. Support-conductor 22, which is here shown broken before passing through its vacuum seal, may be sealed through the envelope in essentially the same manner as is support-conductor 23. The active filament consists of a single strand wire 25 of a refractory metal, such as tungsten, the strand ends of which

are affixed, as by welding, to support conductors 22 and

23. Between the strand ends, the filament is formed into a multiple hairpin shape producing an active filament structure such that the length of the active structure is considerably larger than its overall diameter. In making this reverse hairpin shaped filament, a plurality of bights or hairpin bends are formed. The bight 25a at the supported end of the filament structure is also supported ultimately upon the vacuum envelope. As may be seen in the structure of Figs. 2 and 3 this is advantageously accomplished by means of wire connection member 26, one end of which is fastened around bight 25a and the other end of which is connected to insulator 27 as by crimping in place, using a metallic strap 28 wrapped around insulator 27. As illustrated the insulator is in turn advantageously connected to support-conductor members 22 and 23 by relatively rigid wire-like connection means 29 and 30. In this instance the connection means 29 and 30 are fixed in small holes parallel to the axis of cylindrical insulator 27. In other instances the insulator might be supported upon some other means ultimately supported by the vacuum envelope or upon the vacuum envelope itself. The illustrated means of accomplishing the desired end is of particular advantage, however, because of its simplicity. The bights 25b at the opposite end of the filament structure are advantageously joined together through an insulating path by means of fine wire ties 31 and 32, which are wrapped around the filament wire 25 and joined to cylindrical insulator 33. It may be noted that insulator 33, like insulator 27, is advantageously made with a pair of parallel holes extending through the insulator parallel to its axis. The wire ties 31 and 32 may each pass through and be fixed in one of these holes after making the tie connections to the filament strand. Because of the fineness of the tie wires 31 and 32, they will have but a small, almost negligible, cooling effect upon the filament. In general, the relatively small means specifically described for supporting the filament will permit more nearly uniform filament temperature over most of the length of the filament. It is important, of course, that wire members connected to the filament wire 25 such as wires 26, 31, and 32, be of high heat resistance, such as molybdenum, tungsten or tantalum. It is also important that the insulator 32 have high heat resistance and be incapable of retaining occluded gases which will be released when the insulator is heated to the very high temperatures to which it might be subjected in its particular location adjacent the filament. I have found that insulators composed of materials such as alumina or materials such as quartz are satisfactory.

In a modified form of the filament, bight 25a may be connected to a support-conductor which is sealed through the vacuum envelope. A terminal for such a lead might be used to divide the filament in half and to place the two halves of the filament in parallel, or it might be connected to a center tap on the filament transformer. In the event that such an extra lead is used, the filament may be made in two separate hairpin shaped pieces each having an end connected to the extra support-conductor or it may be a single strand, essentially like strand 25. In either event, the elements of my invention are still applicable.

The tube structure of Fig. 1 advantageously employs flexible connection means to extend support conductors 22 and 23 outside of the vacuum envelope. Filament terminals are advantageously mounted on a metallic base 36 of shallow cup-like shape. One terminal 37 is insulated from the base 36 by spool shaped dielectric means 38. The other terminal may be either similarly insulated or connected to the base without insulation. The latter choice is frequently taken in those cases where the terminal in question is grounded. The terminals are prong shape for easy coupling to circuitry.

The illustration of my invention as specifically described thus far, concerns its use in its simplest form, what may be described as a W-shaped filament. When

higher emission is required of the filament, a longer strand bent to form more bights may be employed.

Figs. 4 and 5 illustrate such a filament structure employing a single strand 40 of refractory metal filament wire having seven bights. The ends of this strand occur at the same end of the filament structure and are advantageously affixed to support-conductors 41 and 42 in the same manner employed in the structure of Figs. 2 and 3. In this instance, however, there are a plurality of bights 40a at the envelope supported end of the filament. These bights may be individually connected as shown by separate metallic conductors 43 to a single cylindrical insulator 44 by means of similar, but separate, strap connectors 45. Means connecting the cylindrical insulator 44 ultimately to the tube envelope may include wire-like members 46 and 47 joined to support-conductors 41 and 42. In the alternative a plurality dielectric members may be employed for each of the bights in the manner of the Fig. 1 construction which, insulators are ultimately supported on the vacuum envelope. Various other means of supporting the bights 40a ultimately on the vacuum envelope will occur to one skilled in the art, and such means as are within the limits of the claims are within the scope of my invention.

The bights 40b at the end of the filament unsupported by the envelope may be connected together as shown in Fig. 6 or as shown in Fig. 7. If connections are made as shown in Fig. 6, the arrangement of each connection is similar to that of Figs. 2 and 3, i. e., each adjacent pair of bights is connected by a different insulator. Using this Fig. 6 construction, fine wire tie members 49 and 50 are wrapped around the filament strand, and these tie wires are in turn connected to and insulated from one another by insulator 51, which may be a cylinder of alumina as previously described. In the alternative, bracing of the type shown in Fig. 7 using tie wires 53 and a single insulator 54 may be employed. Both of these means for bracing the otherwise unsupported ends of the filament have merit. The construction of Fig. 6 is advantageous from the standpoint that the ties join the various bights in the directions of the primary forces acting to drive the filament bights apart. On the other hand, the bracing of Fig. 7 is simpler and more easily constructed than that of Fig. 6. It employs but one tie wire 53 for each of the bights 40b, all of which ties connect all the bights to a single insulator 54. The Fig. 7 construction will tend to allow the free ends of the bights to relocate themselves symmetrically around the insulator. This relocation is small in amount and may not be of great disadvantage despite the fact that the filament described is basically an asymmetrical type of filament. The filament relocation permitted by the Fig. 7 type bracing may make a slight difference in the operating characteristics of the tube, however.

The usefulness of my novel filament structure is not confined to tubes like the one specifically described and illustrated in Fig. 1. Different numbers of tube elements may be employed with my filament and the elements may vary in shape and size. The filament itself may also vary in shape and size, e. g., a generally cylindrical shape might be more widely used than the tapered form of Figs. 4-7. Modification in the shape and appearance of filament bracing and support members is also contemplated within the scope of the claims. Likewise, minor changes in the envelope supported end of the active filament structure shall not remove the modified structure from the scope of the claims. For instance, the use of additional support-conductor members is possible, and such members may be either connected to a bight at the envelope supported end of the filament or connected to filament strand ends. In the latter case, more than one filament strand will be used. It is even conceivable that these novel filament structures be used in parallel within a vacuum envelope. All such minor modifications in

structure are intended to be within the scope and spirit of my invention.

I claim:

1. An electron tube embodying a pair of relatively closely spaced elongated electrodes, one of said electrodes comprising an elongated filament structure embodying a length of filament wire formed into a plurality of bights and having its ends both located at the same end of the filament structure and in spaced relation to the bights, and spacing means for retaining the bights in spaced relation from the other electrode and from each other comprising an electrical insulating member disposed between the bights and connected to the respective bights by separate relatively fine high thermal resistance wires secured directly to the filament wire, the connecting wires being of a diameter substantially smaller than the diameter of the filament wire.

2. An electron tube embodying a pair of relatively closely spaced elongated electrodes, one of said electrodes comprising an elongated filament structure embodying a length of filament wire formed into a plurality of bights and having its ends both located at the same end of the filament structure and in spaced relation to the bights, and spacing means for retaining the bights in spaced relation from the other electrode and from each 25

other comprising an electrical insulating member disposed between the bights, and lengths of relatively high thermal resistance wire wound upon respective bights and secured to respective spaced portions of the insulating member 5 whereby the temperature of the filament wire will be substantially unaffected by the spacing means.

3. An electron tube embodying a pair of relatively closely spaced elongated electrodes, one of said electrodes comprising an elongated filament structure embodying a length of filament wire formed into a plurality of bights and having its ends both located at the same end of the filament structure and in spaced relation to the bights, and spacing means for retaining the bights in spaced relation from the other electrode and from each other comprising a non-gas-emitting electrical insulating member 10 disposed between the bights, and lengths of relatively high thermal resistance wire wound upon respective bights and secured to respective spaced portions of the insulating member whereby the temperature of the filament wire will 15 be substantially unaffected by the spacing means.
